UNITED STATES PATENT OFFICE.

JAMES W. KENT, OF BROOKLYN, NEW YORK.

MACHINE FOR CUTTING PAPER.

SPECIFICATION forming part of Letters Patent No. 231,813, dated August 31, 1880.

Application filed January 22, 1880.

To all whom it may concern:

Be it known that I, JAMES W. KENT, of Brooklyn, in Kings county, and State of New York, have invented certain new and useful 5 Improvements in Machines for Cutting Paper, &c., of which the following is a specification.

My improvements consist in the combination, in a machine for cutting paper and like 10 material, of a clamp for holding the paper, means for actuating the same to clamp or exert a pressure on the paper, and means for adjusting the clamp to the paper before it is actuated to clamp or exert a pressure on the paper, whereby a very desirable and effective 15 operation of the clamp is attained.

They also consist in the combination, in a machine for cutting paper and like material, of a knife, and preferably radius-bars, connecting the knife to a fixed part of the frame, 20 levers extending transversely of the machine, and connected at their outer ends with the knife and at the inner ends to a crank carried by a rotary shaft extending longitudinally of the machine, whereby a simple and effective mechanism for operating the knife is attained.

They also consist in details and combinations of parts hereinafter described and 30 claimed.

In the accompanying drawings, Figure 1 is a front view of a paper-cutting machine embodying my improvements. Fig. 2 is a back view thereof. Fig. 3 is a central longitudinal 35 section of the same, taken on the plane of the line $x x$, Fig. 1; and Fig. 4 is a horizontal section taken on the plane of the line $y y$, Fig. 3.

Similar letters of reference designate corresponding parts in all the figures.

40 Δ designates the table of the machine, where the paper or other material to be cut is placed. It may be of wood or other suitable material, and supported by a frame-work consisting of side pieces, B, and cross-pieces or stretchers B'. Any desired style of gages may be employed in connection with the table to facilitate the proper adjustment of the paper or other material before it is subjected to the knife.

45 C designates a clamp for holding the paper in position on the table while being cut. It

consists of a bar extending across the table and connected at the ends by connecting-rods D with levers E, which extend lengthwise of the machine in close proximity to the side pieces, B, of the supporting frame-work of the machine. At the forward end these levers E are connected, by means of connecting-rods F, to the sides of wheels G, mounted on a shaft, H, which is so supported in bearings near the front of the machine that it may be turned by means of a hand-wheel, I, or otherwise, to adjust the wheels G into different positions. These wheels really form adjustable fulcrums for the levers E, and in order that they may not, except when desired, change their positions, I preferably provide their peripheries with ratchet-teeth and combine with them a pawl or pawls, J, to prevent them from turning backward. Such pawl or pawls will be provided with a convenient handle for disengaging them from the ratchet-teeth.

It is intended that the forward ends of the levers E be adjusted by the mechanism just described to suit the pile of paper to be cut and bring the clamp down upon it before exerting the clamping pressure on the clamp.

The rear ends of the levers E are connected to a yoke, K, arranged at the back of the machine, and impelled downward by a cam, L, 80 arranged on a rotary shaft, M; hence on the rotation of the latter the said levers are made to draw down the clamp C on the paper with great force, so that it will hold the paper securely in position.

85 A counter-balance consisting of a weight or a spring, N, secured to the frame-work of the machine and to the yoke K, returns the latter to its normal position when released from the action of the cam L.

The rotary shaft M is actuated through a gear-wheel, M', mounted on it, and a pinion, O', mounted on a shaft, O, that is driven by means of a large bevel-gear wheel, O², mounted on it, and a pinion, P', or a pinion, P², on the 90 driving-shaft P.

To provide for changing the throw or swing of the levers E, I may employ a wedge, X, arranged under the table Δ , and capable of adjustment forward and backward by a lever, Y, 100 connected with it near the front of the machine, to limit the upward motion of the yoke

K more or less, and consequently the action of the cam L upon it.

Q designates the knife of the machine. It is connected by radius-bars R to a cross-bar, 5 B², of the frame-work of the machine, and travels up and down through suitable guides or ways in the side pieces, B, of the said frame-work, deriving a longitudinal shearing action from its connection to the radius-bars. It is 10 connected at the ends, by connecting-rods S, to the outer ends of levers T, extending transversely of the machine, and connected by links U to a yoke, U', on a wrist or pin, p, constituting a crank on the front of a wheel, 15 V', which, as here shown, is a gear-wheel mounted on a shaft, V, extending longitudinally of the machine and deriving motion from a pinion, W', on a shaft, W. This shaft W, by a large bevel-gear wheel, W², derives motion 20 from the pinion P', or a pinion, P², on the driving-shaft P.

The connecting-rods S may be made of sections connected by turn-buckles, whereby their length may be adjusted, if desirable.

25 The pinions P' and P² are loose on the driving-shaft P, but may be separately locked to turn therewith by means of clutches P³, arranged on the shaft, so as to be adjustable thereon along the splines or feathers. These 30 clutches P³ have connected to them arms P⁴, which are mounted on a slider-bar, P⁶, extending transversely across the machine and susceptible of being shifted by a lever, P⁵, extending nearly to the front of the machine. 35 By means of this lever the clutches P³ may be adjusted to release both pinions P' and P², and hence the machine may be stopped without stopping the driving-shaft; or the clutches may be adjusted to release one pinion from 40 and lock the other to the driving-shaft; and hence the machine may be driven forward for work or reversed without altering the driving-shaft or its actuating mechanism.

It will be seen that by my invention I produce a very simple and compact machine, 45 which may be readily stopped and started, driven forward for work, and reversed without altering the driving-shaft, which provides for adjusting its clamp and for subsequently 50 forcing the clamp down upon the paper in a very effective manner, but without waste of power, and which has a very powerful knife-operating mechanism.

Although shown in connection with a machine designed to be operated by power, my 55 improvements may, with great advantage, be embodied in a machine suitable to be operated by hand.

What I claim as my invention, and desire to secure by Letters Patent, is—

60

1. The combination, in a machine for cutting paper and like material, of a clamp for holding the paper, means for actuating the same to clamp or exert a pressure on the paper, and means for adjusting the clamp to the 65 paper before it is actuated to clamp or exert a pressure on the paper, substantially as specified.

2. The combination, in a machine for cutting paper and like material, of a clamp for holding the paper, levers for actuating the clamp, adjustable fulerums for said levers, whereby the clamp is adjusted to the paper before it is actuated to clamp or exert a pressure on the paper, and a cam for actuating the clamp to exert a pressure on the paper, substantially as specified.

3. The combination, in a machine for cutting paper and like material, of the clamp C, connecting-rods D, levers E, connecting-rods 80 F, wheels G, yoke K, cam L, and a counter-balance for readjusting the levers, substantially as specified.

4. The combination, in a machine for cutting paper and like material, of a knife, levers 85 extending transversely of the machine, and connected at their outer ends with the knife and at their inner ends to a crank carried by a shaft extending longitudinally of the machine, substantially as specified.

5. The combination, in a machine for cutting paper and like material, of a knife, radius-bars connecting said knife with a fixed part of the frame, levers extending transversely of the machine, and connected at their outer ends 95 with said knife and at their inner ends with a crank carried by a shaft extending longitudinally of the machine, substantially as specified.

6. The combination, in a machine for cutting paper and like material, of the knife Q, 100 radius-bars R, connecting-rods S, levers T, links U, yoke U', and crank p, substantially as specified.

7. The combination, in a machine for cutting paper and like material, of a clamp, the cam L for actuating the clamp, shafts and gears M M' O O' O², a knife, the crank p for operating the knife-shafts and gears V V' W W' W², and the driving-shaft P, with its pinion P' or P², substantially as specified.
